UNITED STATES PATENT OFFICE.

HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,254,657.

Specification of Letters Patent. Patented Jan. 29, 1918.

Application filed March 13, 1915. Serial No. 14,106.

To all whom it may concern:

Be it known that I, HENRY P. CLAUSEN, a citizen of the United States, residing at Mount Vernon, in the county of Westchester and State of New York, have invented certain new and useful Improvements in Telephone-Exchange Systems, of which the following is a full, clear, concise, and exact description.

10 This invention relates to telephone exchange systems of the central energy type and has for its object the production of improved signaling means for such systems.

In accordance with one feature of this invention, means are provided at a central office, whereby after the calling subscriber's receiver has been restored to the switchhook, the calling subscriber may, by a subsequent removal of the receiver from the switchhook, 20 cause the operation of recall signaling means at the central office, thereby indicating to the operator that another connection is desired.

In accordance with another feature of this invention, means are provided at the central office whereby, after the answering plug has been inserted in the jack of a calling line, signaling means are caused to operate if a listening key is not at once actuated and will continue to operate until the listening key is 30 actuated.

This invention is illustrated in the accompanying drawing in which all apparatus is shown in its normal and unactuated position.

There is shown in the drawing a telephone exchange system containing one embodiment of this invention and comprising the usual subscribers' stations, A and B, and a cord circuit C located at the central office for interconnecting the subscribers' stations. It 40 is believed that this invention will be fully understood from a description of the operation of the system shown in the drawing, and it will be so described.

Supposing subscriber A wishes to converse with subscriber B, A removes his receiver from the switchhook, thereby completing a circuit from battery 5, through one winding of line relay 7, contact 8 of cutoff relay 9, line wires 10 and 11, contact 12 of cutoff relay 9 and the other winding of line relay 7 to battery 5. Current in this path actuates line relay 7, completing a circuit for line signal 13.

The operator observing the line signal 13

inserts the answering plug in the jack indicated by line signal 13, thereby closing a circuit from battery 25 through contact 26 of relay 27, supervisory signal 28, resistance 24, sleeve contacts of answering plug and jack and winding of cutoff relay 9 to ground. Current in this path actuates cutoff relay 9, severing the circuit of line relay 7, thereby effacing line signal 13. A circuit is also completed from battery 50 through winding of relay 22, resistances 23 and 24, sleeve contacts of answering plug and jack and winding of cutoff relay 9 to ground. Current in this path actuates relay 22 which opens its contact 21. The insertion of the answering plug also closes a circuit from battery 14 through winding of relay 15, ring contacts of the answering plug and jack, line wires 10 and 11, and the tip contacts of jack and answering plug to battery 14. It is to be noted that relay 22 operates before relay 15. Current in this path actuates relay 15 which closes its contact 20 completing a circuit from battery 14 through contact 20 of relay 15, winding of relay 27, resistances 23 and 24, sleeve contacts of answering plug and jack and winding of cutoff relay 9 to ground. Current in this path actuates relay 27 which opens its contact 26 and closes contact 51. Closure of contact 51 completes a circuit from battery 25 through interrupter 52, winding of pilot relay 53, contact 51 of relay 27, supervisory signal 28, resistance 24, sleeve contacts of answering plug and jack and winding of cutoff relay 9 to ground. Since the interrupter 52 is in circuit with supervisory signal 28, this signal will flash intermittently until listening key 30 is operated. Also pilot relay 53 will be intermittently energized, thereby intermittently closing the circuit of pilot signal 54 until listening key 30 is operated. The operator now operates listening key 30 and connects the operator's telephone set across the talking strands of the cord circuit and asks the desired number of the calling subscriber. In operating listening key 30, contact 55 thereof is closed, thereby completing a path from battery 14, through contact 20 of relay 15, contact 55 of listening key 30, resistances 23 and 24, sleeve contacts of the answering plug and jack, and winding of cutoff relay 9 to ground. The completion of this circuit short circuits relays 22 and 27 which re-

lease. Relay 22 in releasing, closes its contact 21, establishing a short circuit for relay 27. Relay 27 in releasing opens its contact 51, removing the interrupter 52 from the 5 circuit of supervisory signal 28, and closes its contact 26. Supervisory signal 28 is now shunted by low resistance 23 and does not operate. Finding the desired number to be that of subscriber B, the calling plug is inserted 10 in the jack corresponding to B's line, completing a circuit from battery 31, through supervisory signal 32, resistance 33, sleeve contacts of the calling plug and jack and the winding of cutoff relay 34 to ground. Current 15 in this path operates supervisory signal 32 and actuates cutoff relay 34, cutting line relay 35 from line wires 36 and 37. The operator now restores listening key 30 to its normal position and operates ringing key 20 38, connecting the source of ringing current 39 to B's line to operate the ringer 40 at station B. Subscriber B, upon removing his receiver from the switchhook in response to the operation of ringer 40, completes a path 25 for direct current from battery 14. The completion of this circuit operates relay 45 which completes a circuit from battery 14 through contact 46 of relay 45, resistances 47 and 33, sleeve contacts of the calling plug 30 and jack, and the winding of cutoff relay 34 to ground. Resistance 47 shunts supervisory signal 32, causing this signal to be effaced.

Upon finishing the conversation, subscribers A and B restore their respective 35 receivers to the switchhooks, whereupon relays 15 and 45 release, permitting supervisory signals 28 and 32 to operate to give disconnect signals. If the operator is not busy, the answering and calling plugs 40 are removed from the jacks and all apparatus returns to normal. Suppose, however, that as is frequently the case during busy periods, the operator does not immediately take down the connection, and suppose further 45 that subscriber A desires to immediately make another call. He removes his receiver from the switchhook, thereby causing supervisory signal 28 to intermittently flash, signifying to the operator that subscriber A desires another connection. The 50 manner in which supervisory signal 28 is caused to flash will now be described. When the receiver at substation A is restored to the switchhook, upon the completion of the conversation, the release of relay 15 removes a short circuit from about relay 22, whereupon 55 relay 22 is actuated due to a flow of current from battery 50 through the winding of this relay. The actuation of relay 22 opens its contact 21, thereby removing a normal short-circuit of relay 27. Upon the subsequent removal of the receiver at substation A from its switchhook relay 15 is operated, completing a circuit from battery 14, through contact 60 20 of relay 15, winding of relay 27, re-

sistances 23 and 24, sleeve contacts of the answering plug and jack, and the winding of cutoff relay 9 to ground. Current in this path actuates relay 27 which opens its contact 26 and closes its contact 51. The closure of contact 51 completes a circuit from battery 25, through interrupter 52, winding of pilot relay 53, contact 51 of relay 27, supervisory signal 28, resistance 24, sleeve contacts of the answering plug and jack and the winding of cutoff relay 9 to ground. Since the interrupter 52 is in circuit with supervisory signal 28, supervisory signal 28 70 will flash intermittently. Pilot relay 53 will be intermittently energized, thereby intermittently closing the circuit of pilot signal 54. As long as A's receiver is off the switchhook, supervisory signal 28 and pilot signal 54 will flash intermittently until the operator 75 operates listening key 30. The operation of listening key 30 closes contact 55, thereby short-circuiting relay 27 which releases and disconnects the interrupter from the circuit hereinbefore traced. Since the listening key 30 is operated, the operator 80 may communicate with subscriber A and ascertain his wants.

In telephone systems heretofore used, the operator, being quite busy at frequent intervals, often inserts the answering plug in the 95 jack of a calling line and forgets to actuate the listening key, whereby the calling subscriber is delayed and annoyed by having to operate the switchhook to attract the attention of the operator. In a telephone system 100 embodying the present invention, the unsatisfactory condition just mentioned is overcome and the subscriber obtains much better service. It will also be seen that should the operator, after ascertaining the wants of the 105 calling subscriber, forget to insert the calling plug, or after inserting the calling plug, forget to ring the wanted subscriber, the calling subscriber may readily attract the attention of the operator by merely moving 110 the switchhook down and then up, whereupon both the supervisory signal 28 and the pilot signal 54 will flash intermittently.

It will be seen that by the use of the cord circuit embodying this invention the calling 115 subscriber may, at any time after the answering plug has been inserted into the jack of the calling line, and provided the listening key is in its normal position, cause the supervisory signal 28 and pilot signal 54 to intermittently flash, thereby attracting the attention of the operator more readily than could otherwise be done.

While only one calling and one called subscriber's line is shown, for the sake of simplicity, it is to be understood that many such lines may terminate at the central office and that each line may be multiplied to the various sections of the switchboard. In this description several batteries have 125 130

been referred to, but it is to be understood that a common battery may be substituted therefor and such is the usual practice.

What is claimed is:

5. 1. A telephone exchange system comprising a plurality of telephone lines, a link circuit for interconnecting the lines, a signaling device, interrupter mechanism, an operating circuit for the signaling device including the 10 interrupter mechanism completed upon connection of the link circuit with a calling telephone line, an operator's telephone set, a listening switch for connecting the operator's telephone set in circuit with the connected telephone line, and means responsive to the actuation of the listening switch for interrupting the operating circuit.
2. In a telephone exchange system, a plurality of telephone lines, a link circuit for 20 interconnecting the lines, a signaling device, interrupter mechanism, a relay operating upon connection of the link circuit with a telephone line to include the interrupter mechanism in circuit with the signaling device.

vice, an operator's telephone set, a switching 25 device for including the operator's telephone set in circuit with the connected telephone line, and means actuated upon the operation of the switching device for causing the de-energization of said relay.

3. In a telephone exchange system, a plurality of telephone lines, a link circuit for interconnecting the lines, a signaling device, a circuit therefor, interrupter mechanism, a relay operating upon connection of the link 35 circuit with a telephone line to include the interrupter mechanism in circuit with the signaling device, a listening key, and a circuit completed upon the actuation of the listening key to cause the de-energization of 40 said relay.

In witness whereof, I hereunto subscribe my name this 12th day of March, A. D., 1912.

HENRY P. CLAUSEN.
